(57) **CLAIM**

The ornamental design for an automobile spoiler, as shown and described.

DESCRIPTION

FIG. 1 is a left perspective view of an automobile spoiler embodying the ornamental design constituting my invention;

FIG. 2 is a front view of the automobile spoiler of FIG. 1; FIG. 3 is a top view of the automobile spoiler of FIG. 1; FIG. 4 is a bottom view of the automobile spoiler of FIG. 1; and,

FIG. 5 is a left side elevational view of the automobile spoiler of FIG. 1, the right side elevational view being mirror symmetrical.

The broken lines are for illustrative purposes only and form no part of the claimed design.

The automobile spoiler is shown on an enlarged scale in FIGS. 2-5.
